Application August 22, 1940, Serial No. 353,702

14 Claims. (Cl. 126—9)

My present invention relates generally to portable stoves and more particularly to a stove of this nature, in this instance being a portable stove complete in detail in all the parts and combinations thereof for the purposes set forth, capable of effective service under various conditions. The present invention is a continuation-in-part of application Serial No. 203,833 filed April 23, 1938, for Portable stoves, which became abandoned September 1, 1940.

An object of my present improvement is to provide a portable stove that will be more efficient and serviceable and will give tourists, campers and out door health seekers the benefit of cooking and baking facilities in the open, or on rainy or cold days and nights, in tents or various other covers. This stove and its accessories will give warmth and comfort. A hat full of chips, twigs or small wood faggots, always at hand, when used in this stove will be sufficient fuel for cooking a meal for several persons. One large piece of wood when placed in this stove's fire box, with its draft damper closed, will keep fire overnight, and a tent warm and dry thru the assistance of the stove's accessory appurtenance—a brace-U tube, as hereinafter described.

A further object is to provide a portable stove with compartment doors, both having like serviceable features, void of clumsy hinges and latches, stove doors that stay closed until opened. Another object is to provide a portable stove in whose fire-box compartment may be stored the demountable draft extension parts, charcoal, dry wood, etc., and in whose oven is carried the combined reservoir-duffle carrier in which is packed nesting cooking and serving utensils, making only one package to be stored, carried by hand, vehicle, or checked as baggage.

A still further object is to provide an improved portable stove of the character described, having frames made from band-iron into rectangular form, each frame of itself permanently but pivotally attached to, and specially adapted to be folded about the body of the stove, to protect same when stored or during transportation, and to form supporting means for the stove when erected, and one of extreme rigidity in connection with its able accessory devices, the combined brace-protection plate—frame strutting brace plate and stove top protection cover.

A still further object is the provision of a stove of the character described which may be economically constructed, and in which such parts as are liable to deterioration may be easily and quickly replaced, notably the division reinforce-

ment-plate which protects the main division plate, and in connection therewith houses the combined brace-U tube part.

I provide a portable stove having in place of 5 a hand regulating oven damper, a fixed, draft equalizing baffle-plate. I provide a portable stove void of unnecessary stove-lids and ash pan.

With the foregoing and other objects in view, the invention consists of the novel construction, 10 combination and arrangement of parts illustrated in the accompanying drawings forming a part of the specification, and wherein:

Figure 1 is a perspective view of my portable stove folded up and formed into a compact unit;

15 Figure 2 is a bottom plan view of the stove showing the upper longitudinal extensions of the stove's two frame members each pivotally, and permanently, attached to the stove's bottom plate;

20 Figure 3 is a perspective view of the portable stove shown in assembled position;

Figure 4 is a vertical longitudinal section of the stove assembled;

25 Figure 5 is a transverse vertical section taken along line 5—5 of Fig. 4;

Figure 6 is a vertical section taken along line 6—6 of Fig. 5;

Figure 7 is a transverse vertical section thru 30 the center of the oven compartment and the oven along line 7—7 of Fig. 4;

Figure 8 is a side elevational view of the draft extension parts partly broken away to show mounting means;

Figure 9 is a top plan view of the draft extension part's top plate;

Figure 10 is a perspective view of the mounting means for the cooking utensil duffle carrier;

Figure 11 is a sectional view showing the bolt 40 nut's position within the cooking utensil duffle carrier and the bolt shank and head in position for alignment with the stove's keyhole slot;

Figure 12 is a vertical longitudinal section thru the keyhole slot and its cap plate;

Figure 13 is a perspective view showing the 45 spring-wire pin and the raised half cylinders, from the stove's front plate for receiving the spring-wire pin;

Figure 14 is a perspective view of the stove door, and slot alignment, catch;

50 Figure 15 is an enlarged view of the interlocking means of the stove's frame members;

Figure 16 is a vertical section taken along the line 16—16, of Fig. 15;

55 Figure 17 is a side elevation view of the stove's combined brace-U tube;

Figure 18 is a fragmentary side view of a modified form of a securing means for the frames' connection bars;

Figure 19 is a perspective view of one member of the stove's draft extension parts;

Figure 20 is an elevational view of one of the fastening lugs;

Figure 21 is a plan view of the combined brace-protection plate;

Figure 22 is a perspective view of the baffle hooked support for receiving the oven's connecting flange.

Referring to the drawings, Figs. 1, 2, 3 and 4, show an outer casing (measuring approximately 10 x 17 x 21 inches, as an example) formed of sheet metal, which casing in part comprises one piece of sheet metal forming the bottom plate 1 which, in being formed upwards, at right angles, a relative distance from its transverse center, is made to form the end walls 2 and 3, which end walls at their upward extremities are formed inwardly, see Fig. 4, at right angles to form seats 2^a and 3^a, upon which the top-plate 4, consisting of one piece of sheet metal is seated and securely fastened thereto by suitable means. The back plate 5, Fig. 7, is formed of one piece having, on its four sides, flanges 5^a, formed inwardly at right angles and made to snugly enter and to close the rear aperture of the stove casing and fastened thereto by suitable means. The back plate has two special perforations 5^b, Fig. 5, and an edge sunken perforation 5^c, Fig. 7, aside from the three countersunk perforations, see 5^d, Fig. 5, for reception of bolts, which in conjunction with like bolts, see Figs. 2, 3 and 4, for securing the division plate 10 to the inside of the stove casing.

The casing's front plate 6, see Figs. 1 and 3, is similarly formed with flanges which, in a like manner, enter the front aperture of the stove casing and are fastened thereto by suitable means.

The front plate 6, besides the three countersunk perforations to receive the division plate bolts, has a square opening 6^a, Fig. 13, as an entrance to the fire-box compartment 7, Fig. 4; and also has draft openings 6^b, Figs. 1 and 3, under the square opening, which are partially or fully closed by the sliding damper, shown therewith. To the left of the square opening 6^a, Fig. 13, are two, end-slitted and raised parts 6^c, as formed outward from the surface of the front plate 6, each having a curvature of sufficient height, as rising from the front-plate's surface (to correspond with depressions made in the front plate above, below and between the raised parts 6^c) to take a small spring-wire pin 6^d, and thereby in connection with the stove's one piece door 8, see Fig. 3, having fingers 8^a which are cylindrically formed to receive the spring-wire pin as in connection with the front plate's raised parts 6^c which, in aligned connection, pivots the said door, for co-operation with the stove casing front plate 6 and slot 6^e as a valuable feature of this stove. The fire-box door 8 is formed from one piece of sheet metal and has protruding from its flat, right, central edge, see Fig. 14, a flat "index-finger" joint like part 8^b, having a notch 8^c in its upper edge, the part 8^b is bent inwardly, at a right angle, from the door body. The front plate 6 has a slot 6^e in its face to receive the door part 8^b. The stove door 8, thru its cylindrically formed parts 8^a and the special spring-wire pin alignment therein, and under the front plate's raised and outwardly curved parts 6^c, so

hold, when open, the upper edge of the "index-finger" like part 8^b slightly above a level alignment with its receiving slot 6^e. By hand pressure against the stove door 8, the door part 8^b enters the slot 6^e and the notch 8^c by combined action of the parts 6^e, 8^a and the spring-wire pin 6^d snaps upward and inwardly into an interlocked engagement with the upper border of the slot 6^e, see Figs. 14 and 3. With the hand applied to the stove door ring 8^d, a downward and outward pull (which with intention makes the stove firmer in contact with its ground bearing) is necessary to disengage the notch 8^c from its locked contact with the slot 6^e.

The front plate 6 has, leading into the stove's oven compartment 9, an opening 6^f, Fig. 22, which is much larger than the fire-box compartment opening 6^a; the said openings are closed by like doors having pivotal connections and fastenings alike in connection with the front plate of the stove; the edge metal of the opening 6^f, Figs. 7 and 22, is shown depressed or countersunk sufficiently to form a seat 6^g, having in its upper, right hand edge a notch 6^h, Fig. 22.

The stove casing is divided into a fire-box compartment 7 and an oven compartment 9, by a main division plate 10, Fig. 5 (also see Figs. 4 and 6), removably fastened to the stove casing and dividing the casing into two unequal in size compartments best to suit the purposes.

The division plate 10 is made of a thicker gage metal than the other plates and has its four outer edges formed, at right angles to the said plate, looking toward the oven compartment; the angle parts having, near the angle bends, bolt holes, see Figs. 3, 4, 5 and 6, to correspond with like bolt holes 3^d, Fig. 5, in the stove's casing for removably holding the division plate as within the stove casing. The division plate has a sufficient number of openings 10^a made in its upper surface for the products of combustion to pass thru to the oven compartment 9.

A division reinforcement-plate 11, Fig. 5 (forming a pocket or air-chamber 11^c, in connection with the division plate is shown in Figs. 4, 5 and 6), made and adapted to protect and preserve the division plate intact at the point where from practical use, it was found finally to succumb to the fuel flames. Extending outward from three sides of the oval face of the division reinforcement plate is a limited flat surface thereof which is secured by bolts 11^a to the division plate 10. The reinforcing plate's rear edge 11^b is formed outwardly at right angles, as shown along line 5—5, Fig. 4, to flatly contact in part, the inner surface of the stove's back plate 5, which meeting surfaces mentioned are held in contact by the two cap plugs 12^e, Fig. 5, of the stove's combined brace-U tube 12; without this means the stove's rear fire-box wall, a part of back plate 5, would, in time by fire influence, bulge outward.

When, by excessive use the division reinforcement plate 11 burns thru, it can be unbolted, removed and replaced by a new one, thus preserving the division plate 10.

A double bearing influence in the stove's efficiency is its combined brace-U perforated tube; the latter combining to hold and to distribute heat and thereby to conserve fuel; also is shown its stove plates' bracing effectiveness in combination with the tube's flat-bar 12^a, as shown along line 6—6, Fig. 5, which is welded or brazed to the U tube's rearwardly bearing two arms, see Fig. 17,

and at a right angle thereto, so that the flat-bar will lie flat against the fire-box surface of the division-plate 10, see Figs. 4, 5 and 6, and extend downward and upward, terminating in flanges 12^b, Fig. 6, the lower flange bolted 12^c to the stove's bottom plate 1, Fig. 2, and the upper flange bolted 12^c to the stove's top plate 4, Fig. 3, which arrangement in connection with the brace-U tube rigidity prevents the stove's top plate from sagging at a point first in evidence from much use over flame; and in combination, while independent of the division plate, strengthens and prolongs the life of the division plate 10 in true alignment. The brace-U tube fits snugly into the pocket 11^c, formed as between and by the mentioned alignment of the division plate 10 and its reinforcement plate 11. The arms of the brace-U tube extend rearwardly from its bend; the arms have two intervening braces 12^d made of the same tube material, all U tube parts connecting for the trapping and holding of heat that would escape as thru the stove's draft extension parts, thereby also causing a loss in extra time necessary to collect, handle and consume extra fuel to cover any unnecessary loss of heat aforesaid mentioned. The brace-U tube thru its two arms 12 extends outward thru openings 5^b in the stove casing back plate 5, Fig. 5, only far enough to take on washers 12^d, Fig. 17. The inside surfaces of the brace-U tube's open ends are threaded to take the cap-plugs 12^e, Figs. 5 and 17, each having a one-eighth-inch vent hole thru its center for the escape of a limited amount of heat from the brace-U tube. The positive bearings of the cap-plugs 12^e and the washers 12^d, against the contiguous outer surfaces of the stove casing back plate 5, aided by the support of the flat-bar 12^a, the latter being bolted to the stove casing, and welded to and forming a member part of the brace-U tube, holds the casing back plate 5 in line against reinforcement plate flange 11^b and the brace-U tube in rigidity as affixed, all aiding the portable stove's efficiency and durability. The cap-plug's 12^e protrusion beyond the surface of the casing back plate 5 is very slight.

The stove's oven 13, Figs. 4, 7 and 22, has a strip of metal 13^a of the proper width and length and gage, formed to contact by two-thirds of its width, and to be permanently fastened to, the upper right hand top ledge of the oven 13; the remaining free edge 13^b of the metal strip 13^a is formed to curve over and downward throughout the oven's full length (see Fig. 7) and adapted to interlock with the hook part 14^b, Fig. 4, of the baffle-plate 14 in its full length fore and aft; the baffle-plate in its permanent attachment to the stove casing is secured thereto by its flange-part 14^a, being by suitable means spot welded or riveted, to the inner face of the stove casing top-plate 4, Fig. 4, adjacent to the stove casing draft opening 15, Fig. 1. The end of the oven 13 fits neatly the opening 6^f of the stove casing front plate 6, Fig. 22, as it is introduced therein which introduction is assisted by the operator's eye in seeing the receptive front of the baffle-plate's hook-part 14^b, as seen commencing just behind the notch 6^h, Fig. 22, as made for that purpose in the countersunk seat part 6^g of the opening 6^f in the front plate 6. The rear free edge of the metal strip 13^a readily engages the hook part 14^b of the baffle-plate 14 and as the oven is pushed backward the mentioned interlocked portions, of the baffle plate and the metal strip 13^a hold the oven in true alignment, and the inwardly countersunk hole 13^c, in the center of the oven's back plate, slides over the

receiving bolt 13^d, which bolt relatively passes thru an opening 5^c in the casing's back plate 5, Fig. 7, the bolt being held thereto by a nut 13^e and a supplementary nut 13^f, Figs. 4 and 7, as applied to the bolt, holds the oven securely in place with the flanges 13^d, Fig. 7, of the oven mouth contacting against the seats 6^g with a part of the flange 13^d, then covering the slot 6^h to prevent the escape of any of the products of combustion; thus is provided an oven compartment 9, having a passageway, equally spaced as between the walls of the oven compartment and the oven 13, with a fixed baffle-plate, and its hook-up connection, directing the air products of combustion backward, downward and fully around the oven, except at its upper right hand corner where the baffle-plate 14 has openings 14^c, Fig. 7, of a sufficient size for drawing a limited amount of heat thereto and thru said openings at what otherwise would be the oven's coldest part, the interlocking baffle-plate 14 thus performing a triple service, needing no hand manipulation.

In my former U. S. patents covering improvements in portable stoves an opening was made in the stove's top plate for passage of the products of combustion to be drawn thereto by a draft producing extension part.

In order to have this stove's top plate free of obstruction, for full cooking service, I make a limited opening 15, Fig. 1, having a notch 15^a in its lower border, in the stove casing and plate 3 for the reception of a removable, draft-extension part 16 made of sheet metal, and comparatively of small size, see Figs. 3, 4 and 8, and having a mouth, and lips 16^d to fit into and automatically lock within the opening 15 and notch 15^a contacting edges. The draft extension part 16 has a top-plate 16^a, Fig. 9, having an opening 16^b, which has two notches 16^c extending therefrom, and an L shaped lug 16^e riveted to the center of the top plate's upper lip surface 16^d, Figs. 8 and 9, in a position for the upturned plane of the said lug to contact the inside upper wall of the opening 15, see Fig. 8.

I provide a lug, see Fig. 20, which has shoulders 16^f, a neck, and a head 16^g, see Fig. 8, which lug is riveted to the outside center of the lower lip, of the draft extension part 16, being in situ opposite the lug 16^e, riveted on the upper lip of part 16, but specially aligned to connect with the notch 15^a of the stove casing end plate 3, opening 15.

In connecting the draft extension part 16 to the stove casing end plate 3, the said part 16 is first tilted to permit the upturned plane of the L lug 16^e to enter the opening 15 and to be seated against the inside contiguous surface of the stove casing end plate 3. As the other lips of the draft extension part 16 pass into the opening 16^b, a slight hand pressure will cause the neck of the lug, as between its head 16^g and shoulders 16^f, to snap into an interlocked relation with the notch 15^a of the opening 15, see Fig. 8. The flat, contacting surfaces of the lug's shoulders with the stove casing end plate 3 prevents any rocking motion of the draft extension part 16.

The upturned face of the L lug 16^e, see Fig. 8, prevents the upper aspect of the draft extension part 16 from tilting outward, and the cylindrical draft extension part 17 in situ, Fig. 8, prevents any sliding further inward of the draft extension part 16.

The draft extension part 17 (see Fig. 19, also Figs. 8, 4 and 3), is of a limited size, length and weight for the purpose of perfect draught, and being readily mounted, or dismounted for flatly

packing within the stove, and is blanked-out of sheet metal, as of one piece, so blanked that its features are readily shop-formed as of itself, and in cylindrical form, as shown in Fig. 19, for connection with the opening 16^b in the top 16, Figs. 8 and 9. The part 17, Fig. 19, is provided along its approximately right edge with an out-turned hooking flange 17^a, which is adapted to be received in a clasping manner by a similar in-turned hooking flange 17^b on its left edge for connecting the said edges. From the top margin of the draft extension part 17 to a limited distance down its approximating right edge a strip of its metal is cut away and the remaining strip, a short distance above the right edge of the hooked flange 17^a is bent over to stand out at right angles from its base to form a lug 17^c. From the left top margin of the part 17 to a limited distance down its approximating flange edge a strip of its metal is cut away and a slot 17^d, to receive the right angle lug 17^c, is made in its remaining edge above its in-turned hooking flange, so when the said hooking flanges 17^a and 17^b are clasped in interlocking alignment the right and left vertical edges above the flanges meet when the lug 17^c automatically slips and seats into the slot 17^d and thus prevents the upper reaches of the clasped alignment 17^a and 17^b from being disengaged. From the bottom margin of the part 17, on its right edge and upwards, a slight strip of metal is cut away, another slit is made, the same in width as the flange 17^a; which slit metal extending upwards is bent outward, at right angle, to form the flange 17^e. From the bottom margin of the part 17, on its left edge below the flange 17^b a slit, the width of its in-turned flange, is made upward and the said width of metal is turned upon itself then outward at a right angle to form a lug 17^f; the vertical edge of the metal, as depending below 17^f, inclines inwardly so that when the hooking flanges 17^a and 17^b are in engagement, the inwardly inclined vertical edge, below the lug 17^f, contacts the vertical metal edge below the flange 17^e, thus keeping the lower aspect of the hooking flanges 17^a and 17^b from becoming disengaged, and leaving a space, of a metal thickness (for the edge of 16^b, Fig. 9) as between the flat flange 17^e and the lug 17^f; see Figs. 19, 8 and 3.

A pair of lugs 17^g, same as one shown in Fig. 20, are relatively attached to the draft extension part 17, as shown in Figs. 19, 8 and 3, and are adapted to operate in the notches 16^c, Figs. 8 and 9; in the same manner as heretofore mentioned in describing the interlocking of the draft extension part 16 with the opening 15 and its notch 15^a, in the stove casing and plate 3.

When the draft-extension part 17 is formed by the hand into its cylindrical aspect and the hooked flanges 17^a and 17^b are interlocked, the flange 17^e is relatively introduced into the opening 16^b of the top part 16^a, Fig. 9, so to contact the inner face of the top plate 16^a, adjacent the opening 16^b, as shown in Fig. 8; the lug 17^f at the same time contacts and is seated on that part of the top plate 16^a which intervenes as coming between the flange 17^e and the lug 17^f. The heads of the two lugs 17^g, then being in position to enter the notches 16^c of the opening 16^b, are made to do so and a further push automatically seats, and interlocks their necks as clasped by the metal margins of the notches 16^c; the level surfaces of the horizontal shoulders of the lugs 17^g, contacting the contiguous flat surface of the top plate 16^a of the draft extension part 16, thus prevents any rocking of the draft extension part

17. While the lug, Fig. 20, is shown in the drawings as formed separately and applied to the draft extension part 16, the said lug can be made as a part of the sheet metal comprising the draft extension part 16, by a special forming die made for the purpose; and likewise the two lugs 17^g of the draft extension part 17, can be relatively stamped on and as a part of the one piece metal part 17, by the same special die after the one sheet piece is blanked and ready for shaping into active form.

When it is desired to carry the air products of combustion further away from this stove, when erected for use, a section or more of ordinary 4 inch stove pipe may be secured, to fit in the firebox 7 when packed or when the stove is erected to fit over the top of the draft-extension part 17 of which the protruding lug 17^c, *in situ* in the slot 17^d, will limit the extent downwards of a 4 in. stovepipe.

In the stove casing end-wall 2, relatively near the casing front and back walls are two openings in the form of key-hole slots 2^d, see Figs. 10 and 12, commencing immediately below 2^a of the casing and plate 2, see Fig. 4, which slots have caps 2^b attached by suitable means to the inside face of the casing end wall 2; the said caps have a two-fold purpose namely, to cover inwardly the said key-hole slots thus preventing any escape thru the slots of the products of combustion; each cap has an outwardly looking transverse ridge 2^c which in outline faces the transverse center of the said slots to aid in seating and securely holding bolt heads affixed to any cooking utensil adapted to be thus attached, especially, the utensil-duffle carrier by its bolt attachment feature in connection with the said key-hole slots. As a valuable accessory and working part of the stove an article of necessary utility is provided, namely the combined utensil-duffle carrier 18, see Figs. 1, 3 and 4, made and adapted especially to carry a complete cooking and serving outfit of sixty or more pieces nested therein, and the combined utensil-duffle carrier then to accurately fit into the stove's oven for storage or transportation, see Fig. 1. When the stove is being erected for active use, as hereinafter more fully described, the combined utensil-duffle carrier and its contents are removed from the oven, then the contents from the carrier. The utensil-duffle carrier member is rectangular in form, having a lid 18^a, hinged at 18^b, the lid having a unique countersunk and perforated part in its top to receive and hold the lid's lifter 18^c, standing upright for use, and when closed to lie flat against the lid top, for close packing within the oven.

The upper edges of the utensil-duffle carrier member are curved inwardly and around a wire 18^d, see Figs. 4, 10 and 11, of sufficient caliber to strengthen the mouth border of the member 18, as contacting with its lid 18^a. The side wall 18^e of the utensil-duffle carrier which is to abut the casing end wall 2, has two holes, see Figs. 10 and 11, thru which pass the threaded shanks of round head bolts 18^f; the threaded shanks enter nuts 18^g, attached flatly to the side wall 18^e inside face, the upper flat edges of the nuts contact squarely against the wired border 18^d. When the bolts 18^f are screwed into their respective nuts, their shanks do not extend further into the side walls 18^e than the nut limit, thus not being in the way of the duffle, when packed therein; the bolt heads thus lying against the outside face of plate 18^e do not interfere with the accurate fitting in of the utensil-duffle carrier member within the stove's oven. The bolts are so aligned

in the said member's side plate 18^e that when their shanks are slightly unscrewed, to a thickness of the end plate 2 of the stove casing, the bolt heads 18^f readily enter the circular part of the key-hole slots. A hand pressure downward on the top of the utensil-duffle carrier causes the bolt heads 18^f to pass beyond the transverse ridges 2^c, which hold the bolt shanks in contact thus seated in the lower constriction of the key-hole slots by the combined action of the relative parts mentioned, see Figs. 10, 11, 12, 3 and 4.

The stove casing is provided with a front frame member 19, Figs. 1, 2 and 3, rectangular in form, having horizontal reaches, 19^a and 19^b and upright reaches 19^c and 19^d, made of band-iron of adequate width and gage, and having a reinforcement-bar 19^x permanently attached by its ends to the upright-reaches of the front frame member 19. A like rear frame member 20 is also provided; both frame members are independently but permanently and pivotally attached to the bottom part of the stove casing 1, Figs. 2 and 4, so that when the stove is in the form of the "one package" for storage or transportation the frame member 19, by its several reaches, covers and protects the front edges of the stove casing while the frame's reinforcement-bar 19^x transversely binds against the casing's front plate 6 and its doors in protection and the absolute closure thereof; and in a like manner the rear frame member 20 encompasses and protects the stove's rear edges, while its reinforcement-bar 20^x, Fig. 1, protects the casing's back plate 5.

To secure the frame members 19 and 20, in locked alignment when folded over the stove in its "one package" form, and also to hold the said frame members interlocked in relation when, by their pivotal connection with the bottom plate of the stove casing, the frame members depend therefrom to elevate and support the stove and its parts when in active service, I provide two connection bars 21 pivotally attached to the upright reaches of the rear frame member at 21^a, see Figs. 1 and 2, the said connection bars reach forward to contact and become engaged with interlocking spring-members 19^f attached to the upright reaches of the front frame member 19. The connection bars 21 being identical in construction, adaptation and action; and the cooperative interlocking spring members 19^f, of each other likewise, one of each pair will be described. The connection bar 21 is permanently but pivotally affixed to the upright reach 20^d of the rear frame member 20, at 21^a, and extends forward, terminating in an inwardly curved portion carrying, as thru its lip, a ring and rearwardly thereof, as made thru the connection-bar 21, are two elongated slots 21^d and 21^b, a relative distance apart for the purpose hereinafter described.

I provide an elongated slot 19^e, Fig. 3, in each of the upright reaches of the frame member 19 and to coincide in size and alignment with slots 21^d and 21^b, shown in the connection-bar 21 (see Figs. 1 and 3), to receive a reduced end 19^g of an interlocking spring-member 19^f which is rigidly affixed, at 19^h, to the upright reach of the frame member 19, see Figs. 1, 3, 15 and 16, and which interlocking and release of the reduced-end part 19^g is operated as by hand when applied to an elongated wire ring 19ⁱ, carried by a formed bend 19^j in the upper reach of the interlocking spring-member 19^f. When the front slot 21^d, in the connection bar 21, registers with the slot 19^e in the upright reach of the frame member 19, and the interlocking spring-member's slot-fitting, re-

duced-end 19^g, is by the spring member's action, made to enter the said registering slots, thus is the interlocked relation of the frame members held in a folded over position about the stove.

5 When the frame members by their pivotal action, are made to align under the stove the rear slot 21^b of the connection bar 21, registers with the slot 19^e of the frame member 19, and both said slots register with the reduced end 19^g, fitting therein, thus are the frame members held in the under, connection, support position, to the stove.

The frame members' ground contacting, horizontal reaches 19^a and 20^a are made one-quarter-inch longer than their stove casing attached, horizontal reaches 19^b and 20^b for a double purpose, namely: to give the frames an outward strut as to ground contact to prevent a right to left rocking of the stove when in active use; and when the stove is folded up as shown in Fig. 1 the extra lengths of 19^a and 20^a, one-eighth-inch on each side, permits the frame-members at their extra spread junctures to snugly fit over the contacting edges of the brace-protection plate, 23, see Fig. 1, and to retain the said plate when it is placed in protection to and over the top plate 4 of stove.

The reinforced parts 22, see Figs. 2 and 5, are permanently affixed to the bottom of the stove and are of the pivotal arrangement which permanently attach independently each frame member to the stove casing; the said reinforced parts, are trebled in thickness at their outer ends, but gradually decrease in thickness toward the joints which hold the pintles of the pivotal arrangement; such thickened construction causes the frames 19 and 20, when they are moved to the stove supporting position, shown in Figs. 3 and 5, to have a decided strut away from each other, forward and aft, in their downward reaches, and gives the frame members a firmer support seating on the ground, the frame members being so held in said position by the combined alignment of slots 21^b of the connection bars 21, with the slots 19^e of the upright reaches 19^d of the frame member 19 being interlined by the reduced ends 19^g of the interlocking spring members 19^f. By viewing Figure 2 will be seen tongue like parts of 19^b and 20^b, of the frames 19 and 20, extend therefrom and are cylindrically formed to take each a pintle for connecting the frames to the parts 22 each of which has two tongues cylindrically formed for taking the said pintles for pivotally connecting the said frames to the bottom plate 1 of the stove casing; see also 19^d, 20^d, 22 and 22, Figure 5.

55 To aid the frame members' strutting and interlocking feature described and to prevent any rocking to and fro of the said frames when held in the support position I provide the brace-protection plate 23, see Figs. 21, 1, 3 and 4, made of 60 comparatively stiff, sheet-metal conforming in size and its edges formed to fit over the borders of the stove top, see Fig. 1. The right and left ends of the plate have notches 24, Fig. 21, made to fit the inside surfaces and edges of the upright reaches of the frame members 19 and 20, the said notches being relatively an eighth of an inch further apart fore and aft, on each end of the brace-protection plate, than the relative contacting surfaces therewith of the said upright reaches of frame members so that when the frame members are in their strut supporting position and the brace-protection plate 23 is slightly forced into place, as seated fore and aft on the reinforcement bars 19^x and 20^x, the notches 24 65 contacting the surfaces aforesaid of the upright reaches of frame members 19 and 20, the said notches being relatively an eighth of an inch further apart fore and aft, on each end of the brace-protection plate, than the relative contacting surfaces therewith of the said upright reaches of frame members so that when the frame members are in their strut supporting position and the brace-protection plate 23 is slightly forced into place, as seated fore and aft on the reinforcement bars 19^x and 20^x, the notches 24 70 contacting the surfaces aforesaid of the upright reaches of frame members 19 and 20, the said notches being relatively an eighth of an inch further apart fore and aft, on each end of the brace-protection plate, than the relative contacting surfaces therewith of the said upright reaches of frame members so that when the frame members are in their strut supporting position and the brace-protection plate 23 is slightly forced into place, as seated fore and aft on the reinforcement bars 19^x and 20^x, the notches 24 75 contacting the surfaces aforesaid of the upright reaches of frame members 19 and 20, the said notches being relatively an eighth of an inch further apart fore and aft, on each end of the brace-protection plate, than the relative contacting surfaces therewith of the said upright reaches of frame members so that when the frame members are in their strut supporting position and the brace-protection plate 23 is slightly forced into place, as seated fore and aft on the reinforcement bars 19^x and 20^x, the notches 24

reaches of the frame members, with the lower edges of the connection bars 21, contacting the curved edges of the brace-protection plate, the brace-protection plate thus holds the ultimate strut-support position of the frame members in rigid alignment thus precluding any play whatever between the pivotal arrangement, slots and interlocking spring member alignment of the frame members, when the portable stove is set up, and in active use.

Referring particularly to Fig. 18, a modified form of the connection bar and upright reaches is provided. In this instance the connection bars 21 are provided with slots 1 and 2 to receive a bolt which is secured to the upright reach, and a wing nut 3 is threaded onto such bolt so that when the slot 2 has received the bolt the wing nut 3 may be screwed up tight for securely fastening the connection bar 21 in position. A spring plate 5 is secured at 4 to each upright reach and is adapted to be sprung outwardly when the latch bar 21 is moved downwardly between the frame's upright reach and spring plate 5. The spring plate 5 has a passage which receives the bolt.

To demount the stove from its erected position to its storage, or transportation, compact form, first remove the utensil-duffle carrier from its outside stove connection, pack duffle in it and place the utensil-duffle carrier in the oven. Then remove the draft extension parts from their outside stove connections, flatten the cylindrical part and place in stove's fire-box. Then remove the brace-protection plate from its brace seated contacts, as bearing on the frames under the stove, and place the brace-protection plate in its protection position as contacting the top of stove, see Fig. 1.

By applying a hand pull on the wire rings, lift the connection bars 21 clear of the interlocking attachments; swing the thus disconnected frame members, as by their individual pivotal connections, respectively over the front and rear borders of the stove to protect same and to bind the brace-protection plate to the stove's top; to hold all securely locked and to prevent rattling of the parts swing the connecting bars 21, as by their pivotal connections, forward for their outward slots 21^a, to register with the slots 19^a and to be interlocked therewith by the alignment, as within said slots, of the snugly fitting reduced ends 19^c of the interlocking spring members 19^c; the connection bars also thus protect the end plates 2 and 3, of the stove casing; the brace bar of the rear frame member protecting the rear plate 5 of the stove casing; the brace bar of the front frame member protecting the front plate of the stove casing and the door rings and the stove's doors and holding said doors fully closed in their automatically locked alignment with the stove casing front plate and fully preventing loss of any of the stove's contents; thus is this portable stove, compact, complete, convenient and clean, substantially described all for the purposes as herein set forth.

I claim:

1. A portable stove comprising a casing having top, bottom, back, front and end plates and transversely divided into a firebox and an oven compartment by a removable division plate having a plurality of openings in its upper part and having a reinforcement plate with a recessed portion removably attached to the firebox side of the division plate below said openings, the said two plates having adjacent surfaces in contact and thereby forming a pocket as between them, a

removable oven in the said oven compartment having its walls spaced therefrom, a baffle plate with its forward surface having therein a restricted opening, said baffle plate being attached to the casing top plate and depending therefrom as within the oven compartment and contacting the top of the oven in slidable and hooked up alignment.

2. A portable stove as set forth in claim 1, a U-tube brace nesting in a pocket as formed by said division and reinforcement plates, a flat metal bar permanently attached at right angle to the U tube arms, said flat bar extending downward and upward as between the said division and reinforcement plates, said flat bar ends terminating in right angle seats thereof and bolted respectively to the bottom plate and to the top plate of said casing, the arms of the U tube extending rearwardly between the division and reinforcement plates and through openings in the casing back plate, the said arms terminated by inside threaded ends mounted by vented cap-plugs made to bear against the outer surface of the casing back plate.

3. A portable stove comprising a rectangular outer casing having embodied therein a communicating fire box and oven compartment, a pair of rectangular frames each composed of comparative horizontal reaches and upright reaches, a pair of reinforcement bars and a pair of connection bars, said frames and bars composed of flat metal, special means provided pivotally connecting said frames as front and rear frames in spaced relation to the bottom of said casing, said connection bars pivotally connected opposite each other to said upright reaches of the rear frame, each connection bar provided with two spaced relation slots in its forward extension, each upright reach of the front frame provided therein with an oppositely disposed slot and each said upright reach having an oppositely disposed interlocking spring member attached thereto to align with the interior slot in the said connection bar and the slot in the said upright reach provided to hold the frames aligned in a support position as pivotally connected to the bottom of said casing and depending therefrom, and in another position, the said interlocking spring member to align with the slot in the said upright reach and the posterior slot in the said connection bar to hold the frames as folded equally over the front and rear borders of the stove casing.

4. A portable stove comprising a casing, a division plate dividing the casing into a firebox and an oven compartment and secured to the inner walls of the casing, a reinforcing plate secured at its edges to the division plate and having its major portion spaced from the division plate to form a pocket between the plates, and a reinforcing member disposed within said pocket.

5. A portable stove comprising a casing, a division plate dividing the casing into a firebox and an oven compartment and secured to the inner walls of the casing, a reinforcing plate secured at its edges to the division plate and having its major portion spaced from the division plate to form a pocket between the plates, a reinforcing member disposed within said pocket, said reinforcing member being of tubular formation, and means to vent the interior of said tubular reinforcing member.

6. A portable stove comprising a casing, a division plate dividing the casing into a firebox and an oven compartment and secured to the

inner walls of the casing, a reinforcing plate secured at its edges to the division plate and having its major portion spaced from the division plate to form a pocket between the plates, a reinforcing member disposed within said pocket, said reinforcing member comprising a substantially U-shaped tubular member having its arms extending through one of the walls of the casing, and vented caps closing the ends of the arms of the U-shaped tubular member.

7. A portable stove comprising a casing, a division plate dividing the casing into a fire box and an oven compartment and secured to the inner walls of the division plate and having its major portion spaced from the division plate to form a pocket between the plates, a reinforcing member disposed within said pocket, said reinforcing member comprising a substantially U-shaped tubular member having its arms extending through one of the walls of the casing, vented caps closing the ends of the arms of the U-shaped tubular member, and spaced tubular braces connecting the arms of the U-shaped tubular member within the pocket and communicating with the interior of the U-shaped member.

8. A portable stove comprising a casing, a division plate dividing the casing into a firebox and an oven compartment and secured to the inner walls of the casing, a reinforcing plate secured at its edges to the division plate and having its major portion spaced from the division plate to form a pocket between the plates, a reinforcing member disposed within said pocket, said reinforcing plate terminating at a point spaced a substantial distance below the top of the division plate, there being openings in the division plate above the reinforcement plate to place the firebox in communication with the oven compartment.

9. A portable stove comprising a substantially rectangular casing having front and back walls, a division plate separating the casing into a fire box and oven compartment, said division plate having openings placing the two compartments in communication, a vertical baffle plate disposed in said oven compartment adjacent an end wall of the casing and having its lower edge bent upwardly to form a channel, an oven removably positioned in said oven compartment and having secured to one corner thereof a strip having its free edge bent downwardly to slidably engage in said upwardly facing channel, said oven being spaced from the walls of the oven compartment to provide a draft passage around the oven, said baffle plate having a draft opening therein, the front of the oven compartment having an opening adapted to receive the oven, the forward portion of the oven having a peripheral flange to rest against the front of the casing about the opening in the casing, and means for connecting the rear of the oven with the back wall of the casing to removably secure the oven in operative position within the oven compartment.

10. In a portable stove, a casing having front, back, top, bottom and end walls, and comprising a fire box and an oven compartment, a removable oven, means within said oven compartment, including an upwardly facing channel, for slidably supporting said oven, said casing front plate having an opening affording access to said oven compartment, the margin of said opening having a notch opposite the end of said channel, and said oven having a flange around its mouth adapted, when said oven is inserted in assembled position, to engage and overlap the margin of

said opening and cover and conceal the said notch.

11. In a portable stove of the character described, a casing having top, bottom, back, front and end plates and an oven compartment, a slidably removable oven located in the said oven compartment and spaced from the walls thereof and forming with the walls of the compartment a draft passage around the oven, said oven having 10 a strip affixed thereto, adjacent one corner, the free edge of said strip being bent downwardly, a baffle plate secured to the underside of said casing top plate and depending therefrom in said oven compartment, the said baffle plate terminating 15 along its lower edge in an upwardly facing channel adapted to slidably receive the downwardly bent edge of said strip, said casing front plate having an oven compartment opening for receiving said oven, said opening having a countersunk margin forming a seat for a flange surrounding the oven mouth, said margin having a notch opposite the end of said channel to admit said strip, said oven adapted to be inserted 20 through said opening in the casing front plate into said oven compartment and slidably supported by said baffle plate, a bolt passing through an opening in the back of said casing and a like opening in the rear end plate of said oven, nut means engaging said bolt to hold said oven in position and seat the oven mouth flange against said countersunk margin of said oven compartment opening in such position as to cover said notch therein.

12. A portable stove comprising a casing, a set 35 of hinge members secured to the underside of the casing along a line parallel with but spaced from each side edge of the casing, said hinge members tapering in thickness from their inner edges to their outer edges to provide inclined under surfaces, a pair of approximately rectangular frames formed of bars relatively thin and wide in cross-section, said frames encircling said casing, when in stored position, and each being pivotally connected along the inner edge of one side to the thin outer edges of one set of said hinge members, whereby each of said frames may be swung around said pivotal connection into stove-supporting position, the engagement of the surfaces of the frame side bars with the inclined under 45 surfaces of said hinge members, when said frames have been swung to their limit of movement, causing said frames to diverge downwardly from the casing, and detachable means for bracing said frames to hold them rigidly in such downwardly 50 diverging relation.

13. In a portable stove, the combination with a rectangular casing, of a pair of approximately rectangular frames, each comprising a pair of horizontal and a pair of substantially vertical reaches, means pivotally connecting one horizontal reach of each frame to the bottom of said casing in spaced, parallel relation, whereby said frames may be swung around said pivotal connecting means into a position in which the free 60 horizontal reaches thereof engage the ground to support the stove, and a brace plate constructed to fit in between the four vertical reaches of said frames when in stove-supporting position, said plate having notches in its opposite edges arranged to engage said vertical reaches and interlock therewith, so as to rigidly hold said frames against relative pivotal movement.

14. In a portable stove, the combination with a rectangular casing, of a pair of approximately rectangular frames, each comprising a pair of

horizontal and a pair of substantially vertical reaches, means pivotally connecting one horizontal reach of each frame to the bottom of said casing in spaced, parallel relation, whereby said frames may either occupy a position encircling said casing or be swung around said pivotal connecting means into a position in which the free horizontal reaches thereof engage the ground to constitute legs for supporting the stove, and a brace-protection plate constructed to fit in between the four vertical reaches of said frames

when in stove-supporting position, said plate having notches in its opposite edges arranged to engage said vertical reaches and interlock therewith, so as to rigidly hold said frames against relative pivotal movement, said plate being of such size and shape as to rest upon and conform substantially with the area of the top of the casing, when in stored position, and to be embraced by said frames when in casing-encircling position.

WILLIAM EDWARDS BAXTER.
